SCALP TREATING DEVICE

Filed Oct. 5, 1931

UNITED STATES PATENT OFFICE

CHARLES V. JAMESON, OF CHICAGO, ILLINOIS

SCALP TREATING DEVICE

Application filed October 5, 1931. Serial No. 566,843.

The invention relates generally to scalp treating devices and more particularly to a device for applying a treating liquid to the scalp.

5 An object of the invention is to provide an improved device of this character for applying a heated liquid, such as oil, to the scalp which embodies a liquid reservoir of large capacity, and means for controlling and regulating the flow of liquid therefrom.

Another object resides in the provision of a novel means for producing a positive flow of liquid from the device to the scalp. In this connection, the device is arranged to discharge liquid from a number of hollow members, which are maintained in spaced relation to the scalp during operation to prevent the clogging thereof by dandruff or the like, said spaced relation being such that liquid 10 is withdrawn through the members by cohesive action of the liquid once contact thereof with the scalp has been effected.

A general object of the invention is to provide such a device which is simple in construction and assembly, is efficient in operation and which may be manufactured and sold at a low cost.

Other objects and advantages will become apparent in the following description and from the accompanying drawing, in which:

Figure 1 is an axial section through a device embodying the features of the invention.

Fig. 2 is a plan view of the device looking downwardly in Fig. 1.

Fig. 3 is a transverse section through the device taken along the line 3—3 of Fig. 1.

Fig. 4 is a transverse section taken on the line 4—4 of Fig. 1.

While the invention is susceptible of various modifications and alternative constructions, I have shown in the drawing and will herein describe in detail the preferred embodiment, but it is to be understood that I do not thereby intend to limit the invention 40 to the specific form disclosed, but intend to cover all modifications and alternative constructions falling within the spirit and scope of the invention as expressed in the appended claims.

50 In describing the present invention, it will

be considered that the device is particularly adapted for applying oil or oily preparations either in cool or heated condition to the scalp, but it will, of course, be understood that the device is well adapted for 55 the application of liquids other than those mentioned.

With reference to the drawing, the embodiment of the invention, which has been chosen for illustrative purposes, comprises generally 60 an elongated casing 10 having therein a cylindrically-shaped barrel 11 which houses and mounts the operative parts of the device. In this embodiment, the barrel 11 is a metal cylinder arranged to be received in the outer end of the casing 10 and provided with an internal partition or wall 12 which divides the barrel into two compartments 13 and 14 of unequal size. The compartment designated by the numeral 13 is the larger of the two compartments, is disposed within the outer end of the casing 10 and constitutes the oil receptacle. Extending radially of the barrel 11 from one side thereof is a longitudinally alined row of rods 15 and small-bore 65 tubes 16. The bores in the tubes communicate with the interior of the compartment 13 so that oil may flow therethrough from the compartment. The arrangement of the tubes and rods will be hereinafter more particularly 70 described.

The open face of the compartment 13 is closed in any suitable manner, as by a plug 17 arranged to fit snugly and rotatably therein. Preferably, this plug is fashioned to provide a valve for admitting air to the interior of the compartment. To this end, the portion 18 of the plug which fits within the end of the barrel is provided with an L-shaped bore 19. One end of the bore is arranged to communicate with that part of the compartment 13 which will be an air space when the device is upright in use. The other end of the bore is movable upon rotation of the plug into and out of registration with an aperture 20 appropriately formed in the side of the barrel. It is preferred that the aperture 20 be located in alinement with the row of rods 15 and tubes 16. 85

90 The smaller compartment 14 is arranged 95

100

to receive an electrical heating unit for increasing the temperature of the oil within the compartment 13. One preferred form of heating unit comprises a plug 21 having electrical conductors 22 extending in parallelism therethrough. The ends of the conductors are secured to the opposite ends of a resistance or heating element 23 of conventional construction and these ends of the conductors, as well as the entire element 23, are preferably embedded in an insulating plaster or ceramic mass 24. The plug 21 is receivable within the open face of the compartment 14 and is secured therein in any suitable manner, as by a screw.

The casing 10 is so constructed that the parts may be conveniently assembled and disassembled to permit the device to be easily cleaned. Thus, the casing is bisectional and comprises a handle section 25 and a head section 26, both of which are preferably formed of fibre, bakelite, or the like. The handle section 25 is of substantial length and, at one end, has an internal collar 27 secured thereto and arranged to fit snugly about the end of the barrel in which the heating unit is mounted. Such means as a pin 28 through the handle section 25, collar 27, and barrel 11 secures the parts rigidly together. In this assembly, the conductors 22 extend rearwardly from the barrel 11 through the handle section 25 and are supported in spaced parallel relation to each other and to the handle section by a spider 29 through which the conductors extend. An electric contact plug 30, carrying leads 31 from a source of current (not shown), is receivable within the end of the handle section 25 for engagement with the conductors 22. If desired, a reinforcing collar 32 may be secured about the outer end of the handle section.

The head section 26 is fashioned to slip over the end of the barrel 11 wherein the oil compartment 13 is located and has an elongated longitudinally extending slot 33 (Figs. 2 and 3) for receiving the row of rods and tubes. The head section is larger than the handle section 25 so that the inner end of the head section may fit snugly about the adjacent end of the handle section, as at 34. This enlargement of the head section provides a heat-insulating dead-air space 35 between the barrel and the head section 26. The outer end of the section is held in spaced relation to the barrel in any suitable manner as by a ring 36 interposed between the parts near the outer end of the device. A flange 37 on the plug 17 extends into abutting engagement with the end of the head section 26 and normally maintains the assembly thereof on the device.

With reference to Fig. 1, it will be noted that the rods 15 and tubes 16 have an interspersed relationship. That is to say, in this particular instance there are several rods at

both ends of the row, while throughout the central part of the row, the rods and tubes are alternately arranged. Moreover, it will be seen that the rods are longer than the tubes. This interspersed and different length relationship is an important feature of the invention. Thus, by making the tubes shorter than the rods, the tubes cannot come into direct contact with the scalp when using the device and, therefore, cannot become clogged with dandruff or other foreign matter. By interspersing the tubes and rods, the end of every tube, regardless of how many there may be, is positively held out of engagement with the scalp.

The distance at which the ends of the tubes are maintained from the scalp is predetermined with a considerable degree of exactness. Thus, at the start of an operation, oil will flow through the tubes and form small globules at the ends thereof. The spacing between the ends of the tubes and the scalp, which of course is determined by the difference between the length of the tubes and the rods, should be such that the globules will come in contact with the scalp when the ends of the rods engage the scalp. Subsequent movement of the device along the scalp causes the oil to be drawn through the tubes by the cohesion of the oil. It will be seen, therefore, that the oil will be applied directly to the scalp, as is desired, without applying more than a minute amount to the hair. This action of course occurs when the vent to the interior of the compartment 13, through the aperture 20 and bore 19, is closed by non-registration of these openings. Movement of the plug 17, to bring the openings more or less into registration, will vary the rapidity with which oil may flow through the tubes. For convenience in determining the relationship of the aperture 20 and bore 19, a kerf or notch 38 is provided in the flange portion 37 of the plug, which kerf is arranged to be in alignment with the row of rods and tubes when the aperture 20 and bore 19 are exactly in registry.

Means for supporting the device with the tubes opening upwardly when the device is not in use is preferably provided and one form of such means is shown in Fig. 3 as comprising a wide, roughly U-shaped bracket 39 secured at its ends to the head section 26.

It will be apparent from the foregoing that a novel device for applying treating lotions or oils to the scalp has been provided which is capable of being readily assembled and disassembled, is simple in construction, and which is efficient in operation. The heating unit is located in an independent compartment separate from the liquid reservoir, thereby permitting the liquid reservoir to be of substantial capacity. However, the juxtaposition of the heating unit and the liquid reservoir insures sufficient heating of

the liquid. The amount of liquid delivered by the device may be easily and variably controlled by the operator by merely rotating the plug 17. The liquid delivering tubes cannot become clogged because of the positive spacing of every tube from the scalp by the interspersed rods. Furthermore, the alternating relationship of the rods and tubes insures that the liquid will be evenly applied to the scalp.

I claim as my invention:

1. In a device for applying liquids to the scalp, the combination of a tubular barrel having a transversely extending partition therein dividing the barrel into two axially aligned compartments, a plurality of liquid conducting members leading from one of said compartments, and a heating element disposed in the other compartment.
2. In a device for applying liquids to the scalp, the combination of a tubular barrel having a transversely extending partition therein dividing the barrel into two axially aligned compartments of unequal size, a plurality of ducts leading from the larger of said compartments, and a heating unit disposed in the smaller of said compartments.
3. In a device for applying liquid to the scalp, the combination of a liquid reservoir, a plurality of hollow ducts leading from said reservoir for applying liquid to the scalp, and means providing an air duct from atmosphere to said reservoir, said means being adjustable to vary the effective size of said duct.

4. In a scalp treating device, the combination of a casing constituting a liquid reservoir, said casing having an opening therein, a plurality of ducts leading from said casing and communicating with the interior thereof, a closure member rotatably mounted in said aperture, and an air duct leading from atmosphere and communicating with the air space part of said reservoir, said duct being controllable by rotary movement of said closure member.

5. In a device for applying liquid to the scalp, the combination of a reservoir for liquid having means associated therewith for heating the liquid in said reservoir, and a casing enclosing said reservoir in spaced relation thereto to provide a heat insulated dead air space between said parts.

6. In a device for applying liquid to the scalp, the combination of a liquid reservoir, a plurality of rods extending therefrom, and a plurality of ducts extending from said reservoir in communication therewith, said ducts being of equal length and being shorter than said rods.

7. In a device for applying liquid to the scalp, the combination of an elongated liquid reservoir, a plurality of rods extending therefrom, and a plurality of ducts extending from said reservoir in communication there-

with, said rods and ducts being longitudinally aligned on said reservoir, said ducts being shorter than and having an interspersed relationship with said rods.

8. In a device of the character described, the combination of a liquid reservoir, a plurality of longitudinally aligned ducts communicating with said reservoir, and a plurality of scalp-engaging members of greater length than said ducts, there being a plurality of said members at either end of the aligned row of ducts and a single member intermediate each duct whereby the members positively prevent the engagement of the mouth of every duct with the scalp.

9. In a scalp treating device, the combination of a reservoir for liquid, a plurality of ducts communicating with the reservoir and arranged to discharge axially of the duct toward the scalp, and means for positively maintaining the end of every duct in spaced relation from the scalp.

10. In a device for applying liquid to the scalp, the combination of a plurality of ducts, means for supplying scalp-treating liquid to said ducts, and means for spacing the discharge end of every duct from the scalp such a distance that a globule of liquid formed on the end of the duct will initially contact the scalp to permit the liquid to be thereafter drawn through the duct by the cohesion action of the liquid.

In testimony whereof, I have hereunto affixed my signature.
